(57) **CLAIM**

The ornamental design for toothbrush hanger box, as shown and described.

DESCRIPTION

FIG. 1 is a front elevational view of the toothbrush hanger box showing my new design;

FIG. 2 is a rear elevational view thereof;

FIG. 3 is a left side elevational view thereof;

FIG. 4 is a top plan view thereof; and,

FIG. 5 is a bottom plan view thereof.

The broken lines show portions of the design that form no part of the claimed design.
